UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed July 14, 1923. Serial No. 651,447.

This invention relates to manifolding type-writing machines of the continuous billing type, in which a sheet or several plies of work-sheets are fed around a cylindrical platen, said work-sheets having successive corresponding forms printed thereon. A machine of this type is disclosed in the patent to Wernery & Smith, No. 1,132,055, dated March 16, 1915, in which the web comprises several plies with interleaved shiftable carbon-sheets.

The work-sheets may be fed from any suitable source of supply, over the back of a rearwardly-extending table secured to the typewriter-carriage, thence forwardly through a carbon-carrier on said table, where the carbon-sheets become interleaved between the plies or work-sheets of the web, whence they are fed forwardly and then downwardly and around the platen to the printing point. After a form has been typed, the carbon-sheets are shifted rearwardly relatively to the work-sheets, to a fresh set of forms succeeding the set of forms previously typed. To facilitate the relative shifting of the carbon-sheets and the work-sheets, the platen is mounted in a swing frame, so that it may be raised to enable the straightening out of that portion of the web containing the interleaved carbon-sheets, so that relative shifting of the carbon-sheets and work-sheets may be readily accomplished. The carbon-carrier is, for this purpose, pushed rearwardly to a stop and the work-sheets are pulled forwardly to a suitable gage. The platen is then lowered to its normal typing position, after which the typed set of forms may be severed by a suitable knife. The fresh set of forms may then be typed and may be advanced around the platen by the usual line-spacing mechanism, during which time the carbon-carrier moves forwardly on its table with the carbons and the work-sheets.

In the past, it has been found that, during a rapid line-spacing operation which causes a quick start of the platen, when said line-spacing mechanism is operated, either by hand or by means of motor-operated carriage-returning mechanism, there is a slip occasioned between the platen and the work-web, the latter being held back, due to the inertia of the carbon-carrier which feeds forwardly with the web, during line-spacing

operation, and also due to the weight of the web, which must be overcome.

An object of the present invention is to overcome the above-mentioned difficulty. To this end, there is provided means to move the carbon-carrier forwardly after a carbon-shifting operation, thus producing a slack between the carbon-carrier and the platen, and thus eliminating the necessity of setting the carbon-carrier in motion and that portion of the web behind the carbon-carrier at each line-spacing operation. Said means may comprise a spring which is also effective to hold said carbon-carrier in its forward position, and against the tension of which the carbon-carrier may be moved rearwardly for carbon-displacing purposes.

Another object of the invention is to prevent the web from slipping rearwardly of the machine after the slack has been created. To this end, there is provided a clamp, said clamp being normally effective and having connected thereto a finger-piece which may be carried by the carbon-carrier operating handle. A spring is connected to said finger-piece to normally hold the clamp in its effective position. When it is desired, however, to displace the carbon-sheets relatively to the work-sheets, the clamp-finger-piece is drawn forwardly to actuate the clamp, thus releasing the work-web, so that the carbon-carrier may then be pushed rearwardly relatively to the work-web while the latter is being pulled forwardly to the gage. The clamp is also effective to assist in drawing a fresh supply of web from its source during the forward travel of the carbon-carrier.

A feature of the invention relates to means to keep the web, as slack is produced, from working down behind the rear paper-table and work-web-presenting table.

Another feature of the invention relates to means for preventing the web from piling up between the platen and the paper-table while the slack is being produced.

Other features and advantages will hereinafter appear.

In the accompanying drawings,

Figure 1 is a sectional side view of an Underwood continuous billing typewriting machine, showing the invention applied thereto, the parts being in position for the commencement of typing of a fresh set of forms, sufficient slack having been created be-

hind the platen to be partially taken up during the advancement of the web around the platen.

Figure 2 is a view similar to Figure 1, 5 some of the parts being omitted, and showing the platen swung up to facilitate the straightening out of the web, the carbon-carrier having been shifted rearwardly and the work-sheets drawn forwardly to the 10 gage, the web-clamp being still in its ineffective position.

Figure 3 is a view similar to Figure 2, 15 with some of the parts omitted, the carbon-carrier being still held in its rearmost position and the clamp-operating finger-piece having been released by the typist to render the clamp effective, by means of the spring connected to the clamp-controlling finger-piece, to grip the work-web.

20 Figure 4 is a view similar to Figure 3, and shows the parts in position after the platen has been thrown back to its normal typing position, the carbon-carrier having been advanced by a spring, to its extreme 25 forward position, to create a slack in the web behind the platen, and the typed set of forms being severed.

Figure 5 is a perspective view of the carbon-carrier and its supporting table, showing the carbon-carrier-controlling spring, 30 the carbon-carrier-operating handle and the web-clamp-actuating mechanism.

The invention is shown as applied to an Underwood continuous billing machine disclosed in the above-mentioned patent to Wernery & Smith, in which type-bars 10 when operated by keys, not shown, swing upwardly and rearwardly to print against the front of a cylindrical platen 11 mounted 35 in a swing frame 12 supported on a carriage 13 comprising end bars 14 connected to each other by a rear bar 15 and a front bar, not shown. Said carriage is mounted for letter-feed movements on a rear rail 16 and a 40 front rail, not shown, said rails being supported on the main frame 17 of the machine. The platen is secured to a shaft 18 journaled in end plates 20 of the swing frame.

The machine also comprises a horizontal 50 table 21 extending rearwardly from the machine, and over which a composite web 22, comprising work-sheets 23 and interleaved carbon-sheets 24, is conducted to the platen. Said table 21 comprises two end bars 25 connected to each other by a rear bar 26 and a front bar 27, and is connected to travel with said carriage by brackets 28 secured to the cross-bar 15 of said carriage and connected to the front bar of said table. Said 55 table is provided near its rear end with rollers 30, carried by brackets 31 secured to said table, to run on a rear rail 32 supported by a frame 29 secured to the back of the main frame 17. A carbon-carrier 33, adapted to 60 travel toward and away from the platen, is

provided with rollers 34 to engage rails 35 secured to the end bars 25 to run back and forth on said table. The carbon-carrier comprises a base-plate 36, to the under side of which said rollers 34 are attached, two 70 at each side of the machine. Stepped uprights 37 are mounted on said base-plate, one at each side thereof, on which carbon-blades or holders 38 are detachably mounted, said carbon-blades having the rear ends 75 of the carbon-sheets connected thereto.

The work-web 22, which may be fan-folded or comprise separated plies, may be conducted from any source of supply upwardly at the rear of the machine to a 80 turning bar 40 supported on standards 41 extending from the rear bar 26 of the table 21, said turning bar being provided with side guides 42 for the web. From the turning bar the web extends forwardly through 85 the carbon-carrier 33 where the carbon-sheets 24 become interleaved between the plies 23 of said web and then forwardly over a paper-table 43 supported on the typewriter-carriage 13. Said web is also guided 90 at the upper end of said paper-table by side guides 44 supported on a rock-shaft 45 mounted in the carriage-frame.

The web 22 may be fed around the platen by the usual front and rear feed-rollers 46 95 and 47, respectively, when the platen is rotated, which may be done by the usual line-spacing mechanism comprising the line-space wheel 48, or by means of the usual finger-wheel 50; the usual connections, comprising pinions 51 and gears 52, being made 100 between the line-space wheel 48 and the platen 11.

When it is desired to shift the carbon-sheets relatively to the work-sheets, the 105 platen is swung upwardly by means of the swing frame 12 about a rock-shaft 53 which forms part of the swing frame, the swing frame having been previously released by a spring-pressed handle 54 secured to the 110 rock-shaft 45, said rock-shaft having hook-like elements 55 to engage pins or rollers 56 on said swing frame to hold the platen in 115 its normal typing position. After the platen has been lifted, as shown in Figure 2, the 120 carbon-carrier 33 may be pushed rearwardly by a handle 57 to a stop 58 on one of the rails 35 to draw the carbon-sheets rearwardly, said stop being adjustable according 125 to the length of the forms. At the same time the work-sheets 23 may be drawn forward to bring their leading edges to a gage 60 on a gage-bar 61 supported on a front paper-table 62 forming part of the swing frame. The platen is then lowered to its 130 typing position, so that the typed forms may be severed by a knife 59 before the commencement of typing of a fresh set of forms.

The carbon-carrier 33, instead of traveling forwardly with the web during line-

spacing operation, as in the Wernery & Smith machine, is moved to its extreme forward position after the platen has been lowered to thus produce slack in that portion of the web between the carbon-carrier and the platen. To so position the carbon-carrier, there is herein provided a helical spring 63, one end of which is connected to a bracket 64 secured to the rear bar 26 of the table, 10 the other end of said spring being connected to a pin 65 extending downwardly from the base-plate 36 of the carbon-carrier, said spring 63 being conducted over a pulley 66 mounted on a bracket 67 secured to the forward bar 27 of the table 21. With this arrangement, when the carbon-carrier is pushed rearwardly by means of its handle 57, the spring is stretched over the pulley 66 and is effective to return said carbon-carrier 33 to its forward position as soon as the rearward pressure, of the typist, against said handle is relieved, said carbon-carrier being arrested in its forward position by a fixed stop 68.

25 To ascertain the forward movement of the web 22 with the carbon-carrier, there is provided means to hold said web on the carbon-carrier, said means comprising a clamp 70 having a bar 71 extending between two arms 30 72, pivoted on studs 73, secured to the stepped uprights 37 of the carbon-carrier, said bar 71 engaging fingers 74 disposed beneath the web. The fingers 74 may be of resilient material to equalize any inequalities 35 and thereby effectively secure both of the side edges of the web to the carrier. One of the arms 72 is provided with an upwardly-extending arm 75 having connected thereto at 76 a link 77, the forward end of which 40 is supported on a stud 78 engaging in a slot 80 in said link, the link having a finger-piece 81 located near the finger-piece 82 of the carbon-carrier-operating handle, by which the link may be drawn forward to release 45 the clamp 70. To hold the clamp-bar 71 against said fingers 74, there is provided a spring 83 connected between the link and the carbon-carrier-operating handle, against the tension of which the link may be drawn forwardly, as indicated in Figure 2, to raise the clamp and consequently release the web prior to a carbon-displacing operation. After the carbon-carrier reaches the position indicated 50 in Figure 2, during a carbon-displacing operation, the fingerpiece 81 may be released, as shown in Figure 3, thus permitting the spring 83 to render the clamp effective, after which the carbon-carrier 33 may be drawn forwardly by the connected spring 63 to the position shown in Figure 4, to form a loop 84 in the web to produce the desired slack, the platen having previously been lowered to its typing position.

65 To prevent the web from working down behind the paper-table 43 as the slack is

being produced by the forward movement of the carbon-carrier, there is provided a guard-plate 85 secured to the front bar of the table.

To prevent the web from piling up between the platen 11 and the rear paper-table 43, and also prevent the web from jumping out between the side guides 44, said side guides are provided with inwardly-extending fingers or pins 86 beneath which the web 75 passes.

It will be understood that, after the sheets have been gaged, they are held against the gage-bar 61 to keep their leading edges against the gage 60 while the platen 11 is being lowered to its typing position, and that, during this operation, it is necessary for the carbon-carrier 33 to travel slightly forward toward the platen. It will also be understood that it is desirable to produce the slack in the web after the platen has been lowered to its typing position. To this end, the typist may hold the carbon-carrier against complete forward movement and allow it to move sufficiently forwardly to allow the platen to be swung down to its typing position, after which the carbon-carrier may be released to be completely drawn forward by the spring 63 to thus produce the desired slack in the web.

It will further be understood that, if a web comprising a single ply, or, in other words, a single continuous work-sheet, is used, no carbon-sheets are necessary, and consequently it is not necessary to raise the platen prior to severing a sheet. A form after it has been completed may be advanced around the platen until its leading edge is brought to the gage, after which it may be severed. In this instance, the carbon-carrier serves merely as a means to assist in producing the desired slack in the web, said carbon-carrier being pushed rearwardly relatively to the web after the completion of each form, to thus grip the web at a new place, so that it may be subsequently drawn forward by the spring to produce the slack in the web.

Variations may be resorted to within the scope of the invention, and portions of the improvements may be used without others.

Having thus described my invention, I claim:

1. In a continuous billing typewriting machine, the combination of a carriage, a cylindrical platen on said carriage, a table over which a continuous web, comprising plies of work-sheets with interleaved carbon-sheets, may be conducted to the platen, a carbon-carrier on said table to which the ends of the carbon-sheets are attached, said carbon-carrier being shiftable away from the platen to shift the carbon-sheets relatively to the work-sheets, and means to automatically draw the web forward after the carbon-sheets have been shifted.

2. In a continuous billing typewriting machine, the combination of a carriage, a cylindrical platen on said carriage, a table over which a continuous web, comprising 5 plies of work-sheets with interleaved carbon-sheets, may be conducted to the platen, a carbon-carrier on said table to which the ends of the carbon-sheets are attached, said carbon-carrier being shiftable away from the 10 platen to shift the carbon-sheets relatively to the work-sheets, and a spring to draw the carbon-carrier forward after the carbon-sheets have been shifted.
3. In a continuous billing typewriting machine, the combination of a carriage, a cylindrical platen on said carriage, a table over which a continuous web, comprising 15 plies of work-sheets with interleaved carbon-sheets, may be conducted to the platen, a carbon-carrier on said table to which the ends of the carbon-sheets are attached, said carbon-carrier being shiftable away from the 20 platen to shift the carbon-sheets relatively to the work-sheets, a helical spring, 25 one end of which is connected to the rear of said table, and the other end of which is connected to the carbon-carrier, and a pulley on said table at its forward end over which the spring is conducted, said spring being effective 30 to draw said carbon-carrier forward after a carbon-displacing operation.
4. In a typewriting machine, the combination of a carriage, a cylindrical platen on said carriage, a table over which a continuous web, comprising 35 plies of work-sheets with interleaved carbon-sheets, may be conducted to the platen, a carbon-carrier on said table to which the ends of the carbon-sheets are attached, said carbon-carrier being shiftable away from the platen to shift the carbon-sheets relatively to the work-sheets, a 40 clamp to hold the web against the carbon-sheets, comprising a unitary upper jaw-member and lower jaws co-operating therewith, a finger-piece for moving said upper jaw-member to release said clamp prior to a carbon-shifting operation, means to render said clamp effective after the carbon-shifting operation, and automatic means to draw the 45 web forward after the carbon-sheets have been shifted to produce slack in that portion of the web between the carbon-carrier and the platen.
5. In a typewriting machine, the combination of a carriage, a cylindrical platen on said carriage, a table over which a continuous web, comprising 55 plies of work-sheets with interleaved carbon-sheets, may be conducted to the platen, a carbon-carrier on said table to which the ends of the carbon-sheets are attached, said carbon-carrier being shiftable away from the platen to shift the carbon-sheets relatively to the work-sheets, a member mounted upon the carrier and 60 extending across the web, said member forming 65 an upper jaw of a clamp, resilient members beneath the web and forming lower jaws, a finger-piece to release said upper jaw prior to the carbon-shifting operation, a spring connected to said finger-piece to render said upper jaw effective to clamp the web against said lower jaws after the carbon-shifting operation, a helical spring, one end of which is connected to the rear end of said table, and the other end of which is connected to the carbon-carrier, and a pulley on 70 said table at its forward end over which the last-named spring is conducted, said last-named spring being effective to draw the carbon-carrier forward after the carbon-shifting operation. 75
6. In a machine for typing upon a work-web, the combination of a cylindrical platen, a carbon-carrier movable away from the platen, the carbons being interleaved with 80 said work-web and shiftable relatively thereto when the carrier has been moved away from the platen to free said carbons therefrom, a clamping device for gripping said work-web to the carrier subsequent to the carbon-shifting operation, and means for rendering said carrier self-returning toward the platen with the clamped work-web, whereby 85 to provide a length of slack work-web between said carrier and the platen. 90
7. In a machine for typing upon a work-web, the combination of a cylindrical platen, a carbon-carrier movable away from the platen, the carbons being interleaved with 95 said work-web and shiftable relatively thereto when the carrier has been moved away from the platen to free said carbons therefrom, a clamping device for gripping said work-web to the carrier subsequent to the carbon-shifting operation, means for rendering 100 said carrier self-returning toward the platen with the clamped work-web, whereby to provide a length of slack work-web between said carrier and the platen, and means for preventing said slack work-web from 105 piling up on the platen. 110
8. In a typewriting machine, the combination of a carriage, a platen around which a continuous work-web may be fed, a carbon-carrier movable away from said platen, means for holding the web to the carrier, and a spring to return said carrier toward 115 said platen. 120
9. In a typewriting machine, the combination of a carriage, a platen around which a continuous work-web, with interleaved carbon-sheets, may be fed, a carbon-carrier, a handle to move said carbon-carrier away from said platen, a clamp on said carbon-carrier to grip the web, and a spring to move 125 said carbon-carrier toward said platen to produce slack in said web. 130
10. In a machine for typing upon a work-web, the combination of a cylindrical platen, a carbon-carrier movable away from the

platens, the carbons being interleaved with said work-web and shiftable relatively thereto when the carrier has been moved away from the platen, to free said carbons 5 therefrom, a clamping device for gripping said work-web to the carrier subsequent to the carbon-shifting operation, means for rendering said carrier self-returning toward the platen with the clamped work-web, 10 whereby to provide a length of slack work-web between said carrier and the platen, means for preventing said slack work-web from piling up on the platen, and a shield adjacent the rear of the platen for preventing 15 said work-web from working down behind the carriage of the machine.

11. In a typewriting machine, the combination of a carriage, a cylindrical platen around which a continuous work-web may 20 be fed, a clamp for said web, means to enable said clamp to be moved away from the platen independently of the web, and a spring to return said clamp to draw the web towards the platen.

12. In a typewriting machine, the combination of a carriage, a cylindrical platen around which a continuous work-web may 30 be fed, a table, a clamp movable to and away from the platen on said table, means to enable said clamp to be moved away from said platen independently of the web, and a spring to return said clamp to draw the web over said table towards the platen to produce slack in that portion of the web 35 between the clamp and the platen.

13. In a typewriting machine, the combination of a carriage, a cylindrical platen around which a continuous work-web may 40 be fed, a table, a clamp, a device on said table to support said clamp, by which the clamp is movable to and away from the platen, a finger-piece to release said clamp to enable it to be moved away from the platen independently of the web, and a spring to return said device with the clamp 45 to draw the web over said table towards the platen to produce slack in that portion of the web between the clamp and the platen.

14. In a typewriting machine, the combination of a carriage, a cylindrical platen on 50 said carriage, around which a continuous work-web may be fed, means to draw the work-web towards the platen to produce slack in said web, and a shield at the rear of the carriage to prevent the slack-part of the web from working down behind the carriage.

15. In a typewriting machine, the combination of a carriage, a cylindrical platen on 55 said carriage, around which a continuous work-web may be fed, a paper-table at the rear of the platen, over which the work-web is conducted, means to draw the web towards the platen to produce slack in the web, and a plate at the rear of the carriage to prevent

the slack-part of the web from working down behind the paper-table.

16. In a continuous billing typewriting machine, the combination of a carriage, a cylindrical platen on said carriage, around 70 which a web comprising continuous work-sheets may be fed with interleaved carbon-sheets, means to so condition the web that there may be effected a relative shifting between the carbon-sheets and the work-sheets, 75 and guides for said web, and means to prevent jumping out of the web from between the end guides when the web is conditioned as stated.

17. In a continuous billing typewriting 80 machine, the combination of a carriage, a cylindrical platen on said carriage, around which a web comprising continuous work-sheets may be fed with interleaved carbon-sheets, means to so condition the web that 85 there may be effected a relative shifting between the carbon-sheets and the work-sheets, end guides for said web, and fingers on said end guides to prevent jumping out of the web from between the end guides when the 90 web is conditioned as stated.

18. In a continuous billing typewriting machine, the combination of a carriage, a cylindrical platen on said carriage, around 95 which a web comprising continuous work-sheets may be fed with interleaved carbon-sheets, end guides for said web, means to lift said platen to enable the carbon-sheets to be shifted relatively to the work-sheets, and means on said end guides to retain the 100 web between said end guides when the platen is lifted.

19. In a typewriting machine, the combination of a carriage, a cylindrical platen on said carriage, around which a continuous 105 work-web may be fed, means to draw the web towards the platen to produce slack in said web, and means disposed around the side edges of said web to prevent the slack-part thereof from piling up on the platen. 110

20. In a typewriting machine, the combination of a carriage, a cylindrical platen on said carriage, around which a continuous work-web may be fed, means to draw the web towards the platen to produce slack in 115 said web, a paper-table over which the web is conducted to the platen, and means associated with said table and disposed around the side edges of said web to prevent the slack-part thereof from piling up between 120 the platen and the paper-table.

21. In a typewriting machine, the combination of a carriage, a cylindrical platen on said carriage, around which a continuous work-web may be fed, means to draw the 125 web towards the platen to produce slack in said web, a paper-table over which the web is conducted to the platen, end guides for said web, and means on said end guides to prevent the slack-part of the web from 130

piling up between the paper-table and the platen.

22. In a machine for typing upon a work-web, the combination of a cylindrical platen, a carbon-carrier movable toward and from the platen, the carbons being interleaved with said work-web and shiftable relatively thereto, and means yieldingly holding said carrier in a forward position near the platen to form a loop of loose work-web between the carrier and the platen, during typing, thereby preventing tension on said work-web at a line-spacing operation.

23. In a machine for typing upon a con-

tinuous work-web, the combination of a cylindrical platen, a carbon-carrier movable toward and from the platen, the carbons being interleaved with said work-web and shiftable relatively thereto, and means for automatically moving the carrier to a forward position near the platen, and for retaining said carrier in such position during typing, to respectively form and maintain a loop of loose work-web between said carrier and the platen, thereby preventing tension on the work-web at a line-spacing operation.

JOHN WALDHEIM.
